CLEATED ATTACHMENT FOR STREET SHOES

Natalie A. Frisch, 6900 Bobbyboyar Ave., and Hubert J. Vallis, 22942 Vost St., both of Canoga Park, Calif. 91304

Filed Feb. 28, 1973, Ser. No. 336,718

Term of patent 14 years

Int. Cl. D2—04

U.S. Cl. D2—317

FIG. 1 is a perspective view of a cleated attachment for street shoes showing our new design;

FIG. 2 is an enlarged top plan thereof;

FIG. 3 is a side elevational view thereof;

FIG. 4 is a bottom view thereof;

FIG. 5 is a top plan view of another embodiment shown of our design for a cleated attachment for street shoes;

FIG. 6 is a bottom view thereof;

FIG. 7 is a side elevational view thereof; and

FIG. 8 is an enlarged cross section view of a cleat illustrating the hollow interior thereof.

I claim:

The ornamental design for a cleated attachment for street shoes, substantially as shown and described.
